HAND TRUCK

John B. Smith, Atlanta, Ga., assignor to The Smith-Byrd
Company, Inc., Atlanta, Ga., a corporation of Georgia

Filed Oct. 6, 1960, Ser. No. 62,402

Term of patent 14 years

(Cl. D14—3)

FIG.1

FIG.6

Fig. 1 is a rear perspective view of a hand truck showing my new design;

Fig. 2 is a right side elevational view thereof;

Fig. 3 is a left side view thereof;

Fig. 4 is a rear view thereof;

Fig. 5 is a top plan view thereof; and

Fig. 6 is a front view thereof.

I claim:

The ornamental design for a hand truck, as shown.
